(57) **CLAIM**

The ornamental design of an electrical connector housing, as shown and described.

DESCRIPTION

FIG. 1 is a front-top-right perspective view of a first embodiment electrical connector housing showing our new design.

FIG. 2 is a back-bottom-left perspective view of the electrical connector housing shown in FIG. 1.

FIG. 3 is a front view of the electrical connector housing shown in FIG. 1.

FIG. 4 is a back view of the electrical connector housing shown in FIG. 1.

FIG. 5 is a right side view of the electrical connector shown in FIG. 1 taken along line 5-5 of FIG. 3.

FIG. 6 is a left side view of the electrical connector housing shown in FIG. 1 taken along line 6-6 of FIG. 3.

FIG. 7 is a top view of the electrical connector housing shown in FIG. 1 taken along line 7-7 of FIG. 3.

FIG. 8 is a bottom-view of the electrical connector housing shown in FIG. 1 taken along line 8-8 of FIG. 3.

FIG. 9 is a front-top-right perspective view of a second embodiment electrical connector housing showing our new design.

FIG. 10 is a back-bottom-left perspective view of the electrical connector housing shown in FIG. 9.

FIG. 11 is a front view of the electrical connector housing shown in FIG. 9.

FIG. 12 is a back view of the electrical connector housing shown in FIG. 9.

FIG. 13 is a right side view of the electrical connector shown in FIG. 9 taken along line 13-13 of FIG. 11.

FIG. 14 is a left side view of the electrical connector housing shown in FIG. 9 taken along line 14-14 of FIG. 11.

FIG. 15 is a top view of the electrical connector housing shown in FIG. 9 taken along line 15-15 of FIG. 11.

FIG. 16 is a bottom-view of the electrical connector housing shown in FIG. 9 taken along line 16-16 of FIG. 11.

FIG. 17 is a front-top-right perspective view of a third embodiment electrical connector housing showing our new design.

FIG. 18 is a back-bottom-left perspective view of the electrical connector housing shown in FIG. 17.

FIG. 19 is a front view of the electrical connector housing shown in FIG. 17.

FIG. 20 is a back view of the electrical connector housing shown in FIG. 17.

FIG. 21 is a right side view of the electrical connector shown in FIG. 17 taken along line 21-21 of FIG. 19.

FIG. 22 is a left side view of the electrical connector housing shown in FIG. 17 taken along line 22-22 of FIG. 19.

(Continued)

FIG. 23 is a top view of the electrical connector housing shown in FIG. 17 taken along line 23-23 of FIG. 19; and, FIG. 24 is a bottom-view of the electrical connector housing shown in FIG. 17 taken along line 24-24 of FIG. 19. The broken lines shown represent portions of the electrical connector housing that form no part of the claimed design.
